PILLOW CASE OR SIMILAR ARTICLE OF BED LINEN

Ralph H. August, New York, N.Y., assignor to Cannon
Mills Company, Kannapolis, N.C., a corporation of North Carolina

Filed July 31, 1967, Ser. No. 8,056

Term of patent 14 years

(Cl. D92—26)

FIG. 1 is a plan view of a pillow case showing my new design, the reverse side being substantially identical thereto. The pillow case is shown broken away for convenience of illustration.

FIG. 2 is an enlarged plan view of the portion of the pillow case enclosed within the rectangle 2 of FIG. 1.

The essential features of my design reside in the full line disclosure.

I claim:

The ornamental design for a pillow case or similar article of bed linen, substantially as shown and described.
